UNITED STATES PATENT OFFICE.

EPHRAIM CULVER, OF SHELBOURNE, AND THOMAS J. POMEROY, OF EAST HAMPTON, MASSACHUSETTS.

IMPROVEMENT IN WINDOW-SASH FASTENERS.

Specification forming part of Letters Patent No. 38,290, dated April 28, 1863.

To all whom it may concern:

Be it known that we, EPHRAIM CULVER, of Shelburne, in the county of Franklin and State of Massachusetts, and THOMAS J. POMEROY, of East Hampton, in the county of Hampshire and State of Massachusetts, have invented a new and useful Method of Holding and Fastening Window-Sashes; and we do hereby declare the following to be a full and exact description of the construction and operation of the same, reference being had to the accompanying drawings, as forming part of this specification.

In order that others may understand the nature of our invention, we will proceed to describe the construction and operation of the same.

We place in front of the sash on one side a perpendicular metallic rod, C C. We secure the upper end by a screw cut thereon, screwing the rod into the top casing of the window, or any other way to make it fast in the direction of D. The lower end of the rod is secured to the side casing by the short arm G.

We pass the rod C through two perforated posts, A and B, which posts are secured one to the upper and one to the lower sash, by means of the enlarged base. We fix the sash at any desired height by the thumb-screw E or F. The sash is raised, the posts glide freely along the rod, and a turn of the thumb-screw fixes and fastens the sash at any desired point. We do not confine the position to the side of the sash, but attach the fasteners to the side, the middle, or any other point most convenient.

What we claim as our invention, and desire to secure by Letters Patent, is—

The rod C, the posts A and B, and the thumb-screws E or F, in combination, for the purpose herein specified.

EPHRAIM CULVER.
THOMAS J. POMEROY.
